UNITED STATES PATENT OFFICE.

EDWARD KINGSLEY JONES, OF PORTLAND, OREGON, ASSIGNOR OF ONE-HALF TO THEODORE JOHN KERN, OF SAME PLACE.

DESIGN FOR AN INSCRIPTION-PLATE.

SPECIFICATION forming part of Design No. 25,062, dated January 21, 1896.

Application filed July 29, 1895. Serial No. 557,507. Term of patent 14 years.

To all whom it may concern:

Be it known that I, EDWARD KINGSLEY JONES, of Portland, in the county of Multnomah and State of Oregon, have invented and produced a new and original Design for an Inscription-Plate, of which the following is a full, clear, and exact description.

Reference is to be had to the accompanying drawings, forming a part of this specification, in which—

Figure 1 is a face view, and Figs. 2 and 3 are sectional views, of a plate embodying my new design.

The design relates to inscription-plates designed to be applied to sidewalks at street-corners, adapted to receive street-names, advertisements, and the like, and the leading

feature of the design consists in the configuration of the plate, the same presenting a straight back edge *a* and a front edge *b* that is in general in the form of a curve, the plate further presenting semicircular ends or side edges *c*.

Minor features of the design are the wavelike effect at the front edge and the short curves *d* that join the straight back edge *a* and the semicircular side edges *c*.

I claim—

The design for an inscription plate herein shown and described.

EDWARD KINGSLEY JONES.
